US00D538223S

(12) **United States Design Patent** (10) **Patent No.:** **US D538,223 S**
Yang (45) **Date of Patent:** **** Mar. 13, 2007**

(54) **USB BATTERY CHARGER**

(76) Inventor: **Fu-I Yang**, 5th Floor, 101, Hsin Pu 8th Street, Taoyuan City (TW)

(**) Term: **14 Years**

(21) Appl. No.: **29/229,026**

(22) Filed: **May 3, 2005**

(51) **LOC (8) Cl. 13-02**

(52) **U.S. Cl. D13/107; D14/356**

(58) **Field of Classification Search** D13/107-110, D13/118-119, 184; D14/251, 253, 432, 434, D14/356, 435; 320/107-115; 455/573; 439/638
See application file for complete search history.

(57) **CLAIM**

The ornamental design for a USB battery charger, as shown and described.

DESCRIPTION

FIG. 1 is a left perspective view of a USB battery charger showing my new design;

FIG. 2 is a right perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the design, showing the use thereof.

The broken line showing is included for the purpose of illustrating environment features and forms no part of the claimed design.
